(57) **CLAIM**

The ornamental design for a mousetrap, as shown and described.

DESCRIPTION

FIG. 1 is a front, top and right side perspective view of a mousetrap showing my new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
FIG. 7 is rear, top and left side perspective view thereof.
The broken lines illustrate portions of the mousetrap that form no part of the claimed design.

1 Claim, 6 Drawing Sheets
